UNITED STATES PATENT OFFICE

2,447,202

MUD MIXER

James Richard Nowery, Shreveport, La.

Application September 14, 1945, Serial No. 616,239

11 Claims. (Cl. 259—26)

1

This invention pertains to a method and apparatus for the automatic introduction of admixes into the drilling fluid for wells. It is well known that the principal use for such fluids is with rotary drills in drilling oil and gas wells when the fluid is pumped through the drill stem to the drilling bit at the bottom of the hole, and then upwardly around the drill stem to the top of the ground. This functions to carry or float the cuttings from the bit to the top of the well and hold them in suspension when circulation is interrupted, to plaster the walls of the holes and to control any pressures encountered below the surface.

To accomplish this the fluid must be of the proper density and viscosity to give the fluid a greater specific gravity than water. Different chemicals and admixes may be used, which include phosphates, tannic acid compounds, caustic soda and soda ash. The admixes include weight materials, organic and chemical gel forming colloidal matter.

It is an object of this invention to provide an apparatus and method which permits of the accurate mixing of both powdered and liquid chemicals and admixes to the drilling fluid at a predetermined rate to insure the proper control, consistency and rate of flow of the fluid at all times.

It is a further object of this invention to provide a machine of such capacity for the chemicals and admixes that are to be used to insure uninterrupted operation for a run of several hours duration without further attention.

A still further object is to eliminate the necessity of operators after the controls have been adjusted for the proper discharge of the dry and wet chemicals and admixes.

Another object is to prevent a waste of the chemicals and admixes since the discharge from the storage containers can occur only when the mud stream is in motion and the mud motor is functioning.

Still another object is to permit of a plurality of admixes under control of the operator, dependent of the demand for changes in mixtures.

A still further object is to provide apparatus for easy dumping of the chemicals and admixes into the storage containers of the machine.

Another and still further object is to provide for the discharge of the exhaust drilling fluid from the mud motor to the mud pits.

An additional object is to provide for the discharge of the chemicals and admixes from the chemical storage containers with respect to the movement of the drilling fluid.

2

Another additional object is to provide apparatus for the proper agitation and mixing of the chemicals, admixes and drilling fluid.

An additional and still further object is to provide for the screening and prevention of the entry of foreign matter into the storage containers.

Another additional object is to provide easy access to the interiors of the various portions of the apparatus for purposes of cleaning.

10. One more object of the invention is to provide for introduction of live steam or air into the liquid storage containers which, in addition to the mechanical agitators for the dry storage containers, will serve to agitate, thoroughly mix, and hold in suspension, the chemicals contained in the wet storage containers, thereby insuring the exact proportions for ready use at all times.

The invention possesses other objects and features of advantage, some of which, with the foregoing, will be set forth in the following description of the preferred form of the invention which is illustrated in the drawings accompanying and forming part of the specification. It is to be understood, however, that the invention is susceptible to variations in excess of the showing made in the accompanying drawings and description, and which may be adapted within the scope of the invention as set forth in the claims.

With particular reference to the drawings in which:

Figure 1 is a vertical sectional view of the machine.

Figure 2 is an end elevation showing the mud motor and driving connections and fluid conduits.

Figure 3 is a vertical sectional view taken on the line 3—3 of Figure 1.

Figure 4 is a vertical sectional view through one of the wet chemical storage containers, taken on the line 4—4 of Figure 1, while

Figure 5 is a vertical sectional view taken on line 5—5 of Figure 1, through one of the dry chemical storage containers.

Referring specifically to the drawings, the reference numeral 10 refers to conventional oil field type skid base of welded steel construction, on which is mounted the dry chemical storage assembly 12 and the wet chemical storage tank assembly 14. These assemblies are formed from a fabricated steel body, including the three containers or bins 16, 18 and 20, for the reception of dry chemicals, and the two wet chemical tanks 22 and 24. The dry bins are supported by standards 13 and the wet tanks flange members 19 and 55 I-beams 21 which form the skids of the base.

In the present instance, the three dry bins are designed for a capacity of 11 cubic feet while the wet chemical tanks have a capacity of 36 gallons. It is conceivable that containers of different capacity, or a number in excess of those shown, may be used. However, with the presently sized bins and tanks, the machine will run for several hours without adjustment or change and without refilling.

Each of the dry bins 16, 18 and 20, are equipped with adjustable valves 26, 28 and 30, to permit the discharge therefrom at a fixed rate when the machine is in operation. Similarly, the wet tanks 22 and 24, are provided with a plurality of valves for controlling the rate of flow. However, the flow here is under the control, in each tank, of adjustable valves 32 and 34, and through horizontal pipes 36 from which the chemicals are dropped into the high pressure mixing chamber 74 which will be described later in more detail.

A mud motor 40, is positioned adjacent the chemical storage assembly 14 and consists of a steel case within which is enclosed a paddle wheel or impeller 115, which when the mud is flowing, acts like a water wheel and causes rotation of the motor. The stream of high pressure mud, introduced through valve or choke nipple, after passage through the motor 40, is ejected therefrom through an outlet 39 to an open ditch.

An agitator shaft 42, which passes through the bottom of the dry bins 16, 18 and 20, and below the chemical bins 22 and 24 and is supported in bearings 43, 45, 47, 49 and 51. Although in the present disclosure the agitator shaft 42 is located below the chemical bins 22 and 24, it is conceivable that these bins could be lowered to permit the agitator shaft to also pass through these bins.

The power is transmitted through the mud motor shaft 44, pulley 46, V-belt 48 and pulley 50, the latter being mounted on agitator shaft 42. A take-up construction for the V-belt connection is shown generally at 41. At the opposite end of the tank assembly is another V-belt connection which includes a pulley 52 mounted on shaft 42, V-belt 54, and a pulley 56 mounted on a screw conveyor shaft 58. Agitators 60 are mounted on the shaft 42 in the bins 16, 18 and 20 to keep the chemicals and admixes sufficiently loose and permit of a ready flow therefrom. Clean-out plates 61 are indicated in Figure 5.

The screw conveyor shaft 58 is mounted at 62 and 64 in the conveyor shaft casing 66 and has a blade 68, as indicated in Figure 1. This blade is adapted to pick up and carry the chemicals and admixes through the casing 66 as they are discharged in the proper ratio from the valve openings 26, 28 and 30 in the bottom of bins 16, 18 and 20. These chemicals and admixes travel through the casing 66 to the left in Figure 1 where they drop by gravity through the opening 70 in the casing 66 which is in communication with a vertical shaft 72 in a high pressure mixing chamber 74.

Openings 76 with covers 78 are provided for the wet chemical tanks 22 and 24 to receive the chemicals. In order to agitate and more thoroughly mix and hold in suspension the chemicals contained in the two tanks 22 and 24, live steam water or air is provided from a source, the connection 80 only being shown, valve 82, pipe 84 which is apertured at 86.

Discharge of the wet chemicals from the tanks 22 and 24 is made through the openings 88, valve connections 90, valves 32 and 34, to the openings 94 in the high pressure mixing chamber 74.

An opening 96 is located in each of the bins 16, 18 and 20 to receive a basket-like screen 98 which is supported by the beads 100. A cover 102 is provided for these openings which is pivoted at 104 to enable the cover to swing back and rest upon the handles 105. This construction permits of an easy dumping of the containers of chemicals and admixes while the basket-like screen sifts the chemicals and admixes and precludes the entry of foreign matter which would tend to clog the discharge from the bins.

The apparatus is activated by a high pressure stream of mud or drilling fluid which enters through conduit 106 to fitting 108 where it splits, part of the mud going through the control valve 110, piping 112, L 114 and then into the mud motor. After the force of the mud is spent in operating the motor, it is discharged through the large open port 39 into an open ditch. In the drawings, the control valve 110 is provided with a handwheel 116 for operation. However, choke nipples can be substituted for this valve 110, and a valve 118 controlling the rate of mud from the mud supply. The mud diverted at fitting 108 passes through conduit 120 to the mixing chamber 74. It is appreciated that the volume and intensity of the high pressure mud entering into chamber 74 is under the control of valve 118, or by the substituted choke nipple, while the rate of flow of the mud from its source is under the control of the valve 110, or its substituted choke nipple. As a result the speed of rotation of the mud motor, transmits, and controls, the agitator shaft 42 and the conveyor shaft 58. A guard for the mixing chamber is indicated at 126.

It can be appreciated that the dry chemicals and admixes are discharged through the vertical chutes 72 into the chamber 74, the wet chemicals through conduits 90, and the mud or drilling fluid, under pressure, through jet nozzle 124. The introduction of the mud under pressure into the mixing chamber serves to pick up and absorb the dry and wet chemicals discharged into the chamber. A connection 128 is provided at the opposite end of the mixing chamber to carry the drilling fluid stream through a flow line to the storage pits for conditioned drilling fluid.

Operation

The drilling mud enters through conduit 106 to the mud motor 40 under the control of valve or choke 110 which regulates the rate of flow and speed of the mud entering the mud motor. The volume and intensity of the mud going to the mixing chamber 74 is controlled by valve or choke 118. The mud motor being operated by the flow of mud furnishes the power to rotate the agitator shaft 42 to thoroughly mix the dry chemicals and admixes in the bins. Power is transmitted through the V-belt connection 54 to the screw conveyor shaft 58 which further mixes the dry chemicals, as they drop at a predetermined rate and predetermined ratio from valve openings 26, 28 and 30, and conveys them to the end of the casing 66. At this point they fall by gravity into vertical shaft 72 to the high pressure mixing chamber 74 and then, with the wet chemicals also discharged into the chamber 74 from valves 32 and 34, are mixed with the drilling mud under pressure from jet nozzle 124. From this chamber, the thoroughly mixed mud and chemicals are carried to the mud or storage pits for subsequent drilling operations.

Through the use of the present machine a proper drilling fluid is made available for a rea-

sonable period of time without further attention, the machine operating automatically as long as there is a flow of mud to the machine. By the use of this machine and regulation of the valves from the wet and dry and admix chemical containers, the rate of addition of these chemicals and admixes is under the definite control of the operator at all times.

While the form of embodiment of the invention as herein disclosed, constitutes a preferred form, it is to be understood that other forms may be adopted, all coming within the scope of the claims which follow.

What is claimed is as follows:

1. A machine for automatically mixing chemicals and admixes with drilling muds comprising a mud motor connected to a source of supply of mud under pressure, a valve or choke nipple for controlling the speed of rotation of said motor, a plurality of dry and wet chemical and admix containers, discharge control means from said containers, a mixing chamber for said chemicals and admixes positioned adjacent said discharge control means, conveying means mounted in said chamber adapted to carry said chemicals and admixes emptying therein to the discharge end of said chamber, the rate of flow of the chemicals being controlled by the speed of the mud motor.

2. A machine for automatically mixing chemicals and admixes with drilling muds comprising a mud motor connected to a source of supply of mud under pressure, a valve or choke nipple for controlling the speed of rotation of said motor, a plurality of dry and wet chemical and admix containers, means for agitating the dry chemicals and admixes operated by said mud motor, discharge control means for said containers, a mixing chamber for said chemicals and admixes positioned adjacent said discharge control means, conveying means mounted in said chamber adapted to carry said chemicals and admixes emptying therein to the discharge end of said chamber, the rate of flow of the chemicals being controlled by the speed of the mud motor.

3. A machine for automatically mixing chemicals and admixes with drilling muds comprising a mud motor connected to a source of supply of mud under pressure, a valve or choke nipple for controlling the speed of rotation of said motor, a plurality of dry and wet chemical and admix containers, means for agitating the dry chemicals including agitators mounted on a shaft passing through said dry chemical containers, said shaft being operatively connected to said mud motor, discharge control means for said containers, a mixing chamber for said chemicals and admixes positioned adjacent said discharge control means, conveying means mounted in said chamber adapted to carry said chemicals and admixes emptying therein to the discharge end of said chamber, the rate of flow of the chemicals being controlled by the speed of the mud motor.

4. A machine for automatically mixing chemicals and admixes with drilling muds comprising a mud motor connected to a source of supply of mud under pressure, a valve or choke nipple for controlling the speed of rotation of said motor, a plurality of dry and wet chemical and admix containers, means for mixing and holding in suspension the wet chemicals in the tanks including a pipe positioned therein connected to a source of live steam, air or water, discharge control means for said containers, a mixing chamber for said chemicals and admixes positioned adjacent said discharge control means, conveying means mount-

ed in said chamber adapted to carry said chemicals and admixes emptying therein to the discharge end of said chamber, the rate of flow of the chemicals being controlled by the speed of the mud motor.

5. A machine for automatically mixing chemicals and admixes with drilling muds comprising a mud motor connected to a source of supply of mud under pressure, a valve for controlling the speed of rotation of said motor, a plurality of dry and wet chemical and admix containers, means for agitating the dry chemicals including agitators mounted on a shaft passing through said dry chemical containers, said shaft being operatively connected to said mud motor, means for mixing and holding in suspension the wet chemicals in the tanks including a pipe positioned therein connected to a source of live steam, air or water, discharge control means for said containers, a mixing chamber for said chemicals and admixes positioned adjacent said discharge control means, conveying means mounted in said chamber adapted to carry said chemicals and admixes emptying therein to the discharge end of said chamber, the rate of flow of the chemicals being controlled by the speed of the mud motor.

6. A machine for automatically mixing chemicals and admixes with drilling muds comprising a mud motor connected to a source of supply of mud pressure, a valve or choke nipple for controlling the speed of rotation of said motor, a plurality of dry and wet chemical and admix containers, means for agitating the dry chemicals including agitators mounted on a shaft passing through said dry chemical containers, said shaft being operatively connected to said mud motor, a final mixing chamber for said wet and dry chemicals and said drilling mud, the rate of flow of each being controlled by said drilling mud at a predetermined ratio.

7. A machine for automatically mixing chemicals and admixes with drilling muds comprising a mud motor connected to a source of supply of mud under pressure, a valve or choke for controlling the speed of rotation of said motor, a plurality of dry and wet chemical and admix containers, means for agitating the dry chemicals and admixes including agitators mounted on a shaft passing through said dry chemical containers, said shaft being operatively connected to said mud motor, a final mixing chamber for said chemicals and said drilling mud, the rate of flow of each being controlled by said drilling mud, said drilling mud introduced into said chamber under control of a valve to vary the volume and intensity of said mud.

8. A machine for automatically mixing chemicals and admixes with drilling muds comprising a mud motor connected to a source of supply of mud under pressure, a valve or choke for controlling the speed of rotation of said motor, a plurality of dry and wet chemical containers, means for agitating the dry chemicals including agitators mounted on a shaft passing through said dry chemical containers, said shaft being operatively connected to said mud motor, a final mixing chamber for said chemicals and said drilling mud, the rate of flow of each being controlled by said drilling mud, a valve in said mud motor to vary the volume and intensity of said mud.

9. An automatic machine for mixing chemicals and admixes with drilling mud which comprises means for the introduction of mud under pressure to a mud motor and to a mixing chamber, means for introducing chemicals and admixes

into said chamber at a predetermined rate, the proportionate discharge of said chemical and admix being controlled by the speed of said mud motor.

10. An automatic machine for mixing chemicals and admixes with drilling mud which comprises means for the introduction of mud under pressure to a mud motor and to a mixing chamber, means for introducing chemicals and admixes into said chamber at a predetermined rate including valves or chokes to control the discharge of the chemicals and admixes from the source of supply, proportionate chemical discharge means operated and controlled by the speed of said mud motor.

11. An automatic machine for mixing chemicals and admixes with drilling mud which comprises a mud motor, means for introducing mud to said motor under pressure and to said mixing chamber under pressure, means for introducing chemicals and admixes into said chamber at a predetermined rate to effect the thorough mixing

of said mud, chemicals and admixes, said chemical and admix introduction means operated and controlled by the speed of said mud motor.

JAMES RICHARD NOWERY.
